(Cl. D80—9)

To all whom it may concern:

Be it known that I, William L. Stensgaard, a citizen of the United States, residing at Park Ridge, in the county of Cook and State of Illinois, have invented a new, original, and ornamental Design for a Display Device for Yard Goods, of which the following is a specification, reference being had to accompanying drawing, forming part thereof.

Figure 1 is a side elevational view of a display device for yard goods showing my new design;

Figure 2 is a front elevational view of the same device;

Figure 3 is a top plan view of the device;

Figure 4 is a vertical sectional view; and

Figure 5 is a detailed sectional view along the line 5—5 of Figure 2.

I claim:
The ornamental design for a display device
for yard goods, as shown.

W. L. STENSGAARD.
